UNITED STATES PATENT OFFICE

2,498,771

SOLE FITTING MACHINE

Ernest W. Stacey, Beverly, Mass., assignor to
 United Shoe Machinery Corporation, Flemington, N. J., a corporation of New Jersey

Application March 26, 1948, Serial No. 17,275

24 Claims. (Cl. 12—17)

1

This invention relates to machines for operating upon soles of shoes and is illustrated as embodied in a machine of the general type disclosed in United States Letters Patent 2,081,961 and 2,219,341, granted June 1, 1937, and October 29, 1940, on applications filed in my name.

It is an object of the present invention to provide an improved machine of the general type disclosed in the above-mentioned Letters Patent.

The invention consists in novel features hereinafter fully described, reference being had to the accompanying drawings which illustrate one selected embodiment of the present invention.

In the drawings,

Fig. 1 is a front view, partly broken away and partly in section, of the illustrative machine;

Figs. 2 and 3 are left side and plan views respectively, partly broken away and partly in section, of a cutter head of the machine;

Figs. 4 and 5 are vertical sections through the cutter head on lines IV—IV, V—V of Fig. 3;

Fig. 5A shows in side elevation, a cutter adjusting screw driver and a bracket therefor which is mounted upon the cutter head;

Fig. 5B is a view on line VB—VB of Fig. 5;

Fig. 6 is a section on line VI—VI of Fig. 4;

Fig. 7 is a detail view showing portions of mechanism for securing roughing and rounding cutters to a drive spindle of the cutter head;

Fig. 8 is a section on line VIII—VIII of Fig. 1;

Fig. 9 is a front view, partly broken away and partly in section, showing portions of a jack of the illustrative machine;

Fig. 10 is a plan view of mechanism illustrated in Fig. 9;

Fig. 11 is a plan view, partly broken away and partly in section, showing safety mechanism for preventing operation of the machine when there is no pattern mounted upon the jack;

Fig. 12 shows in section a clutch for quickly and effectively stopping rotation of the cutters without stopping a motor drive of the machine;

Fig. 13 is a section on line XIII—XIII of Fig. 1;

Fig. 14 is a plan view illustrating a plurality of patterns of different sizes mounted upon the jack and the operation of a shank reducing cutter upon soles mounted upon said patterns;

Fig. 15 is a section on line XV—XV of Fig. 2 showing a cam for moving a rotary shank reducing cutter to and from an effective position;

Fig. 15A is a section on line XVA—XVA of Fig. 15;

Fig. 16 is a plan view of a modified cam for controlling operation of the shank reducing cutter;

2

Fig. 17 is a section on line XVII—XVII of Fig. 16;

Fig. 18 is a bottom view of rotatable rounding, roughing and shank reducing cutters of the machine arranged in operating nested position in the machine;

Fig. 19 is an illustrative view showing the forepart of the sole being operated upon by the rounding and roughing cutters;

Fig. 20 is an illustrative view showing a shank portion of the sole being operated upon by the rounding and shank reducing cutters;

Fig. 21 is a section on line XXI—XXI of Fig. 19 showing the operation of the roughing cutter and a work holdown formed integral therewith;

Figs. 22 and 23 are side and bottom views respectively of a clamp crosshead of the machine;

Fig. 24 is a perspective view of a sole which has been operated upon by the illustrative machine.

The illustrative machine is described with reference to rounding a block sole 18 to a predetermined outline to form a sole 20 (Figs. 10, 14 and 24), and simultaneously therewith shank 25 reducing the sole at selected localities by roughing cuts to form beveled and roughened shank margins 22 (Fig. 24) extending from opposite ends of a break line 24 of the sole to points rearward of a heel breast line 26 of the sole, and reducing slightly and roughing the forepart and the heel margins 28 of the sole. The purpose of roughing the margins 22, 28 of the sole is to prepare them for the reception of cement by which the sole is eventually to be attached to a shoe.

In performing the above operation a jack 30 (Figs. 1, 2, 9 and 11) and a clamp 32 (Figs. 1 and 2), between which a pattern 34 and the block sole 18 mounted thereon are clamped, are caused alternately to slide and to rotate to traverse the entire periphery of the pattern and, accordingly,

the sole, past rounding, shank reducing and roughing cutters 38, 40 and 42 respectively. As above explained, the cutter 40 in shank reducing the sole, roughens the sole, and the cutter 42 in addition to roughing the forepart and the heel seat margins of the sole, reduces the thickness of said margins to a slight extent. Throughout the detailed description the cutter 40 will be referred to as the shank reducing cutter and the cutter 42 as the roughing cutter.

The cutters 38, 40 and 42 rotate about a common axis 44 (Figs. 2, 4 and 5) and are carried by a cutter head or carrier 46 which is constantly urged by a spring 48 (Figs. 1 and 11) and hereinafter described mechanism associated there-

with toward the jack 30, the operating position of the cutter head being controlled by the engagement of an abutment 50 (Figs. 1 to 5 inclusive) carried by a depending bracket 51 of the head, with an edge or edge face 52 of the pattern. The cutter 40 reduces the shank of the sole 18 and is depressed from an ineffective position shown in Fig. 4 lengthwise of its axis of rotation 44 to move it into a cutting position shown in Fig. 2, by mechanism which will be hereinafter described and comprises a lever 54 (Figs. 2, 4, 5 and 15) pivoted to the cutter head 46 and a cam 56 which is secured in operative position upon the jack 30.

The illustrative machine, except for herein-after described changes, is similar to the machine disclosed in said Letters Patents 2,081,961 and comprises the cutter head 46 secured by screws 58 (Figs. 2, 3 and 4) to a gear housing 60 (Figs. 1, 2, 4 and 5) of a hollow arm 62 formed integral with a hollow post 64 (Figs. 1, 8 and 11) mounted for swinging movement about a vertical column 66 which is secured by screws 68 (only one shown) (Fig. 1) to a stationary main frame 70 of the machine. The post 64 has at its base a flange 72 (Figs. 1 and 8) extending into arcuate recesses of retaining plates 74 secured by screws 76 to the main frame 70.

As in the machine disclosed in said Letters Patent, there is provided a jack and clamp support 78 comprising a hollow carriage 80 (Figs. 1, 8, 9 and 11) having opposed elongated slots or guideways 82 (Figs. 1 and 8), said carriage being mounted upon a guide block 84 which has front and rear tongues 86 slidably fitting in the slots 82 of the carriage, and has a hub portion rotatable in a bearing column 88 (Fig. 1) secured by screws 90 to the main frame 70. As the carriage 80 is moved by mechanism hereinafter disclosed, to the right and left as viewed in Fig. 1 along the guide block 84, it is controlled against swinging movement by a depending arm 92 (Figs. 1, 8 and 11) which is screwed to and forms, in effect, part of the carriage and has a flange 94 fitting in guideways 96 formed in gibbs 98 secured to the main frame 70.

Mounted for rotation in the support 78 is the jack 30, upon which the pattern 34 is positioned and supported, and the clamp 32 which forces the sole to be operated upon against said pattern 34. The jack 30 comprises a pattern holder 100 (Figs. 1, 2, 9 and 10) to a base flange of which is secured by screws 102 (Figs. 1 and 9) a turret plate 104 rotatable in a cylindrical bore 106 of the support 78. The clamp 32 is supported by a shaft 108 (Figs. 1 and 22) rotatable about an axis 110 (Figs. 1 and 9), which is coincident with the axis of the cylindrical bore 106, in a sleeve bearing 112 of an overhanging portion of the support 78, said shaft having a shoulder engaged by a thrust bearing 114. A coupling 116 having trunnions 118 pivoted in a bifurcated end of a lever 120 fulcrumed on a pin 122 carried by an upstanding lug of the support 78, is interposed between the thrust bearing 114 and a collar 124 secured to a reduced upper end of the shaft 108. As will be explained later, the lever 120 is moved clockwise as viewed in Fig. 1 upon depression of a treadle 126 which is pivoted at its rear end to the main frame 70, to raise the shaft 108, which has splined to it a gear 128, and accordingly, to raise the clamp 32. The treadle 126 has pivotally connected to it a rod 123, said rod and treadle being constantly urged to raised positions by a spring 125 interposed between a shoulder of said rod and the main frame 70.

Pivoted to the right end of the lever 120 is a rod 130 (Figs. 1 and 8) which passes through a bore in a lug 132 secured to the support 78, and which has at its lower end a flange 134 (Fig. 1), a pin 136 threaded into said support passing through a slot 138 in the rod and assisting in guiding said rod vertically with relation to the support. Surrounding the rod 130 and interposed between a shoulder of the rod and the lug 132 is a coil spring 140 which constantly urges the rod to a raised position in which, when there is no pattern 34 in the machine, the flange 134 of the rod engages the bottom of the lug 132, the construction and arrangement being such that posts 142, 144 of the clamp 32 normally engage the pattern 34 positioned upon the jack 30 when there is no sole in the machine but cannot move substantially further downward. The treadle rod 123 is operatively connected through mechanism described in detail in said Letters Patent 2,081,961, to a vertically movable rod 145 (Figs. 8 and 11) having secured to its upper end a plate 146 (Figs. 1, 8 and 11) which overlies a flange 148 (Fig. 1) at the lower end of the rod 130, the construction and arrangement being such that depression of the treadle 126 causes the rod 130 to be lowered but permits said rod to slide to the right and left as viewed in Fig. 1 with the support 78, as above explained, during the cycle of operation of the machine.

The screws 102 (Figs. 1 and 9) pass downward through bores in a turret gear 150 which is arranged in concentric relation with the axis 110, and into the upper part of the carriage 80, said screws serving to secure together the holder 100, the turret plate 104, the gear 150 and the carriage 80. The carriage 80 has an internal rack 152 (Figs. 1 and 8), the sides of which are straight and the ends of which are semi-circular, the upper face of said carriage being in engagement with the bottom of the sliding support 78. As above explained the carriage 80 has formed in its sides the slots 82 in which the tongues 86 of the block 84 slidably engage. Rotatably mounted in the block 84, is a shaft 154 (Figs. 1 and 8) to the upper end of which is secured a gear 156 meshing with the rack 152 and to the lower end of which is secured a bevel gear 158 driven by a bevel gear 160 operated by a main drive (not shown) of the machine upon release of a brake 162 (Fig. 1) and the engagement of a clutch 164 in response to forward swinging movement of a hand lever 166 (Figs. 1, 11 and 13).

In order to rotate the shaft 108 together with a crosshead 168 (Figs. 1, 2, 22 and 23) which supports the clamp posts 142, 144 at the same speed as the jack 30, there is provided a train of idler gears 172 (Fig. 1) which are mounted for rotation upon bearing pins 174 carried by the support 78 and are operatively connected, through gears 176, 178 secured to opposite ends of a shaft 180 rotatable in the support, to an idler gear 182 (Figs. 1 and 9) rotatably supported upon a bearing pin 184 which is secured to the support and meshes with the turret gear 150. The holder 100 has a flat upper face 186 (Figs. 2, 4, 9 and 11) upon which the pattern 34 is placed, and a pair of upstanding pins 188 which extend through bores 190 in the pattern 34. The bores 190 in patterns 34 of different sizes are positioned an equal distance from the lengthwise median points of the patterns, said patterns being arranged as illustrated in Fig. 14 upon the holder 100. In such a construction it is desirable to move the clamp posts 142, 144 lengthwise of the patterns 34 in order effectively to clamp the foreparts and

the heel ends of soles of different sizes against corresponding patterns.

The same pattern 34 is used in operating upon both right and left soles of a given size, such pattern being reversed upon the holder 100. Accordingly, in addition to adjusting the clamp posts 142, 144 lengthwise of the pattern with relation to the holder 100, it is desirable to swing such posts to slight extents into different forward and rearward adjusted positions as will be hereinafter described, thus insuring that the posts shall effectively clamp the left and right soles against the patterns. The crosshead 168 which is disclosed in detail in said Letters Patent 2,081,961 comprises left and right slides 192 (Figs. 1, 2, 22 and 23) having guideways 194 (Fig. 22) for receiving a T-shaped portion 196 of a foot plate 198 which is supported upon a pin 199 (Fig. 2) carried by the rod 198 and is normally held in a horizontal position by a spring-pressed plunger 201. The slides 192 are adjustable for equal and opposite movement on the T-shaped portion 196 of the foot plate 198, upon rotation of right and left screws 200, 202 which form part of a shaft 204 rotatably mounted in a boss 206 of the foot plate 198 and which are threaded into bosses 210, 208 respectively of the slides. The shaft 204 is held against lengthwise movement in said boss 206 by a pair of collars 209 pinned to the shaft and engaging opposite sides of the boss 206. The slides 192 are conveniently adjusted lengthwise of the foot plate 198 to arrange the posts 142, 144 for being forced against the forepart and the heel ends of soles of different sizes mounted upon the pattern 34, by turning a knob 212 secured to a shaft 214 which is rotatably mounted in the foot plate and has pinned to it a worm wheel 216 meshing with a worm 218 (Fig. 22) secured to the shaft.

Formed integral with the posts 142, 144 at their upper ends are plates 220 (Figs. 2, 22 and 23) the outer ends of which fit in slots 222 formed between main portions of the slides and retainer plates 224 secured by screws to the slides. The plates 220 have formed in their outer ends, slots 226 (Figs. 2 and 23) for receiving pins 228 secured to the slides 192, said plates 220 and, accordingly, the work clamping posts 142, 144 being secured in either of two angular positions shown in full and dash lines respectively of Fig. 23 and determined by notches 230 in said plates, by spring-pressed detents 232 carried by the slides.

The post 64 which carries the cutter head carrying arm 62 has pivoted to a rearward extension of its lower end a link 234 (Figs. 1 and 11) which is pivoted to an upper arm of an offset bell crank lever 236 secured to a pin 238 journaled in the main frame 70. Pivoted to the lower arm of the bell crank lever 236 is a rod 240 extending into a hollow guide 242 (Fig. 1) threaded into the main frame 70, the spring 48 which is interposed between said guide and a shoulder of the rod 240, constantly urging the post 64 counterclockwise as viewed from above to move the abutment 50 of the cutter head 46 against the edge 52 of the pattern 34. As explained in detail in said Letters Patent 2,081,961, upon the completion of the cycle of the one revolution clutch 164 and movement of the jack 30, a shaft 244 (Fig. 11) corresponding to shaft 36 in said United States Letters Patent 2,219,341 and also to the shaft 562 in said Letters Patent 2,081,961, is rotated counterclockwise as viewed in Fig. 11 to operate through an idler gear 246 rotatable upon a pin 248 secured to the main frame 70, a gear segment 250 and,

accordingly, a shaft 252 to which said gear segment is secured counterclockwise against the action of the spring 48. Secured to the upper end of the shaft 252 is an arm 254 operatively connected through a link 256 (Figs. 2, 4 and 11) to the cutter head 46, counterclockwise movement of such arm as viewed from above causing rearward movement of the cutter head to its retracted or starting position away from the jack 30, in which position it is held by a pawl (not shown) corresponding to the pawl 464 disclosed in Letters Patent 2,081,961.

Adjustably secured by screws 258 (Figs. 2, 3, 4 and 5) in a guideway 260 formed in the cutter head bracket 51 is the abutment 50, a cylindrical work engaging face 262 (Figs. 1, 2, 3 and 4) of which is constructed and arranged to engage, as the hollow arm 62 is swung forward by the above described mechanism operated by the spring 48, the edge 52 of the pattern 34 clamped to the holder 100. In order that the abutment 50 may be removed from the cutter head and replaced in the same operative position in said head, there is provided a rod 263 (Figs. 3 and 5) which has a stop face 266 (Fig. 3) and has its forward end threaded into a thumb nut 264 rotatable in the bracket 51. Interposed between the bracket 51 and the stop face 266 of the rod 263 is a spring 265 for constantly urging the rod rearward in the bracket, a spring-pressed plunger 267 (Fig. 3) in the bracket being forced against the nut 264 to hold said nut in adjusted position. The face 266 of the rod 263 also serves as a stop for insuring against rearward displacement of the abutment 50 from its adjusted position during engagement of the abutment with the pattern 34.

An inclined shaft 268 (Figs. 1, 4 and 12) in the hollow arm 62 has fixed to its outer end a spiral gear 270 (Fig. 4) meshing with a spiral gear 272 (Figs. 3 and 4) keyed to a vertical shaft 274 which is mounted for rotation in bearings 276, 278 (Fig. 4), in the housing 60 and the cutter head 46 respectively and is held against axial displacement. Fixed to the lower end of the shaft 274 between an inner race of the bearings 278 and a retaining screw 280 threaded into the shaft, is a two-part gear 282 meshing with a gear 284 (Figs. 4 and 5) secured to a sleeve 286 of a cutter carrier 288 (Figs. 2, 4, 5 and 18) between a shoulder of said sleeve and a retaining nut 290 threaded onto said sleeve, the gear 284 being provided at its lower end with a transverse channel 292 in which fits a lug 294 of the sleeve. The sleeve 286 is rotatably mounted in a bushing 296 and a ball bearing 298 supported by a sleeve actuator slide 300 which is raised and lowered twice during each cycle of operation of the machine by mechanism hereinafter described in detail. The ball bearings 298 are secured in their operative positions between shoulders of the sleeve 286 and the sleeve actuator slide 300 by a screw 301 threaded into the slide and having oil rings 302.

The cutter carrier 288 is provided with a plurality of circumferentially spaced keyhole slots 304 (Fig. 18) for receiving pins 306 (Figs. 2, 4, 5 and 18) projecting from the cutter 40 to which a plurality of V-shaped blades 310 having threaded studs 308 are secured by nuts. The cutter 40 is secured to the carrier 288 by projecting the pins 306 of the cutter through the enlarged portions of the slots 304 and rotating the cutter with relation to the carrier, causing the pins to enter reduced portions of the slots 304 and to be held in place by a flexible disk 289 (Fig. 4) of the carrier. The blades 310 shank reduce the sole by roughing

cuts as above described to form the beveled shank margins 22.

Extending vertically through bores 312, 314 (Figs. 4 and 5) in the sleeve 286 is a stepped cutter drive shaft 316 which has a reduced upper end passing through bores in spaced circular flanges 318 (Figs. 4, 5 and 6) of an elevating slide 320 (Figs. 3 and 5) mounted for vertical movement in a guideway 322 (Fig. 5) of the cutter head 46. To the flanges 318 of the slide 320 are secured outer races of a ball bearing 324 (Figs. 4 and 5), inner races of said bearing being secured, as best shown in Fig. 6, to the reduced upper end of the shaft 316 by a nut 326 threaded onto the upper end of the shaft. The drive shaft 316 has a bore 328 for receiving a rod 330 which is threaded at its upper end to the shaft 316 and has at its lower end a rounded portion 332 (Figs. 4, 5 and 5B) fitting in a recess 334 in the central portion of the upper face of an abutment plate 336 movable in a transverse slot 338 formed in the drive shaft 316. The cutter drive shaft 316 is rotated in response to rotation of the sleeve 286 through pairs of stepped keys 340 which are mounted in slots 342 of the drive shaft, upper portions of said keys fitting in opposed vertical slots 344 (Fig. 5) of the sleeve.

Fitting on a boss of the drive shaft 316 and partly inside the lower end of the sleeve 286 is the roughing cutter 42 which is provided with keyways 346 for receiving portions of the keys 340 in order to rotate said roughing cutter in response to rotation of the drive shaft. The roughing cutter 42 which as above explained reduces by roughing cuts the margin of the forepart and the heel end of the sole to a slight extent, comprises a plurality of blades 348, teeth of which operate upon the sole with a shredding action, said blades being secured to the main body of the cutter by clamps 350 (Figs. 18, 19 and 21) having threaded shanks for receiving nuts 351. In the illustrative roughing cutter 42 there is positioned just ahead of each of the blades a holddown portion 353 of the associated clamp 350 which straightens out the sole just ahead of the blade, thus insuring against distortion of the sole as it is being operated upon by said blades. The roughing cutter 42 is held against the abutment plate 336 by a spring 352 (Figs. 2, 4 and 5) which engages the lower face of the roughing cutter and is supported by the rounding cutter 38. The rounding cutter 38 is supported in its operating position against the action of the spring 352, by mechanism which will be described presently.

The rounding cutter 38 is bored to fit on a hollow boss portion of the drive shaft 316, said cutter having vertical slots 354 (Figs. 4 and 5) for receiving the lower ends of the stepped keys 340. The rounding cutter 38 has a plurality of straight cutting edges 356 (Figs. 18, 19 and 20) terminating at their lower ends in cutting edges 358 which may be considered as extensions of the cutting edges 356 and which are angularly disposed to the cutting edges 356 and chamfer the sole by beveling cuts adjacent to its grain side.

Slidably mounted in a bore 360 (Fig. 5) at the lower end of the drive shaft 316 is a plunger 362 (Figs. 2, 4, 5 and 7) having shoulders 364 (Figs. 5 and 7) and a projecting pin 366. Pivotally mounted upon pins 368 (Fig. 5) secured to the drive shaft 316 and passing through slots 369 of the drive shaft are pairs of latches 370, upper faces of which are constructed and arranged to

be engaged by the shoulders 364 of the plunger 362 acted on by a spring 372 (Fig. 5) positioned in the lower end of the bore 328 of the drive shaft between the abutment plate 336 and an upwardly facing shoulder of the plunger and serving to force lips 374 of the latches against a lower face of the rounding cutter 38.

The roughing cutter 42 and the rounding cutter 38 may be readily placed in their operating positions in the cutter head 46, after lifting the plunger 362 against the action of the spring 372, to cause the pin 366 of the plunger to swing the latches 370 into positions in which their lips 374 are moved adjacent to each other, the roughing cutter 42 being slid onto a boss portion of the drive shaft 316 with the key 340 fitting in the keyway 346 (Fig. 5) of such cutter, until the cutter engages the abutment plate 336. The spring 352 is thereafter pressed by hand against the bottom of the cutter 42 and the rounding cutter 38 is slid onto another boss portion of the drive shaft in keyed relation therewith against the bottom of the spring 352 then slightly compressed, the operator thereafter releasing the plunger 362 to permit the lips 374 of the latches 370 to swing outward into supporting positions in engagement with the bottom face of the rounding cutter.

When the shank portions of the sole are being operated upon, the shank reducing cutter 40 is in its lowered operating position shown in Figs. 2 and 20, the cutters 38, 40 and 42 being arranged in interspersed relation such as shown in Figs. 2 and 18. When the forepart and the heel end of the sole are being operated upon, the shank reducing cutter 40 is held in its raised position a considerable distance above the sole as shown in Figs. 4, 5 and 19. In shoes having leather heels it is desirable that the beveled and roughened shank margin 22 (Fig. 24) formed by the cutter 40 shall extend from the break line 24 of the sole to approximately the heel-breast line 26 of the sole. In the manufacture of shoes having wood heels the cutter 40 operates upon the sole rearward of the heel-breast line 26, the shank reducing cutter commonly extending to the rear end of the sole as indicated in dotted lines 371 (Fig. 24).

The sleeve actuator slide 390 has a bore 376 (Fig. 5) into which extends a cylindrical portion 378 of a plate 380 secured by a nut 392 to a shoulder of a pin 384 (Figs. 2, 3 and 5) vertically reciprocable in guideways 386 (Fig. 5) of the cutter head 46 which comprises a cover plate 388 (Figs. 3 and 5) removable, after loosening screws 390 to facilitate positioning of the above-mentioned mechanism in said head. The pin 384, as will be explained later, is operatively connected to the lever 54, which is movable in response to engagement with the cam 56, to raise and lower the shank reducing cutter 40 in the direction of its axis 44.

Threaded into the cutter head 46 is a thumb screw 392 (Figs. 2, 3 and 5) having a conical abutment 394, held in different adjusted positions in said head by a spring-pressed plunger 396 which is slidable in said head and is constructed and arranged to enter any one of a plurality of recesses 398 in the screw. Housed in a recess 400 of the drive shaft supporting slide 320 and having its lower end in engagement with a removable plate 402 forming part of the cutter head 46, is a spring 404 which constantly forces a conical face 406 of the slide into engagement with the face 394 of the screw 392, thus retaining the drive shaft 316, and accordingly, the rounding

and roughing cutters 38, 42 in their proper heightwise operating positions in the cutter head. It will be clear from the foregoing that in adjusting the machine for operation, the rounding and the roughing cutters 38, 42 may be moved as a unit lengthwise of the axis 44 into different operating positions in the cutter head by adjusting the thumb screw 392.

After the rounding cutter 38 has been suitably adjusted as above described, the roughing cutter 42 if desirable, may be adjusted in the cutter head 46 to its proper heightwise position with relation to the rounding cutter 38. Such adjustment is quickly effected after the removal of a cover 408 (Figs. 2, 4 and 5) of the cutter head 46, by the use of a screw driver 410 which is mounted for sliding movement and rotation in a bracket 412 supported for swinging movement in the machine frame 70 between an idle position remote from the drive shaft 316 and a position above said shaft. When the bracket 412 is swung against the action of a spring 414 from its idle position to a position over the drive shaft 316, the screw driver 410 is lowered, causing lateral extensions 416 of the driver to fit in slots 418 (Figs. 4, 5 and 6) in a locking sleeve 420 which, as best shown in Fig. 6 is mounted on the upper end of the rod 330 and has at its lower end teeth 422 (Figs. 5 and 6) which are forced into interlocking relation with the teeth 424 at the upper end of the drive shaft 316 by a spring 426 (Fig. 6) interposed between a head of the rod and flanges of the locking sleeve, the head of the rod carrying a pin 428 which fits in the slots 418 of the locking sleeve. As the screw driver 410 is rotated the locking sleeve 420 and accordingly the rod 330 rotates with it, said locking sleeve during such rotation sliding heightwise along the rod against the action of the spring 426 and permitting the teeth 422 of the locking sleeve to override the teeth 424 of the drive shaft 316. When the locking sleeve 420 is not being rotated it secures, through the interlocking teeth 422, 424, the rod 330 to the drive shaft 316 to maintain the rod in its adjusted position upon the drive shaft. The heightwise position of the rod 330 in the cutter head 46 determines the upper limit of movement of the abutment plate 336 (Figs. 4 and 5) when acted on by the roughing cutter 42 elevated by the coil springs 352.

The raised or ineffective position of the shank reducing cutter 40, and accordingly, the lowered effective position of said cutter, may be varied by raising or lowering the sleeve actuator slide 300 (Figs. 4 and 5) by turning a thumb nut 430 (Figs. 1, 2, 3 and 5) which is threaded onto an upper portion of the pin 334 and has a circumferential groove 432 (Figs. 3 and 5) for receiving trunnions 434 carried by the forward bifurcated end of a bell crank lever 436 fulcrumed on a pin 438 (Figs. 2 and 3) secured to the cutter head 46, said lever having a rearwardly extending arm operatively connected by a rod 440 to the rear end of the cam engaging lever 54. The lever 436 is constantly urged counterclockwise as viewed in Fig. 2 by a coil spring 442 (Fig. 3) one end is secured to the cutter head 46 and the other end of which embraces the rear arm of the bell crank lever 436.

As will be explained later, when the hollow arm 62, and accordingly, the cutter head 46 move forward to their effective positions determined by the engagement of the abutment 50 with the edge 52 of the pattern 34 mounted upon the jack 30, the lever 54 by reason of its engagement with the cam 56 swings clockwise as viewed in Figs. 2 and

4 on the cutter head bracket 51. When during rearward movement or retraction of the cutter head 46, the lever 54 is disengaged from the cam 56, the lever acted upon by the spring 442 moves counterclockwise as viewed in Figs. 2 and 4, such movement being limited by engagement of a flange 444 (Fig. 2) of the rod 440 with a stop shoulder 446 of the depending bracket 51 of the cutter head. When the flange 444 of the rod 440 is against the stop shoulder 446, the sleeve actuator slide 300, and accordingly, the sleeve 286 which carries the shank reducing cutter 40 are in their raised positions in the cutter head 46.

The cam 56, which will later be described in detail, is shaped and arranged to cause the shank reducing cutter 40 to be lowered along the common axis of rotation 44 of the cutters, with relation to the rounding and roughing cutters 38, 42 as the shank of the sole moves past the cutter head 46, thereby reducing said shank by roughing cuts to form the beveled and roughened margin 22. When portions of the sole margin other than the shank are passing or traversing the cutter head 46, the shank reducing cutter 40 is in its raised position shown in Figs. 4, 5 and 19, the cam 56 at such time being out of engagement with a button 450 secured to the forward end of and forming part of the lever 54.

When the machine is at rest the jack 30 is positioned as illustrated in Figs. 1 and 11, the rear end of the shank of the sole which is to be operated upon and is supported by the pattern 34 mounted upon the jack, being arranged approximately opposite the axis 44 of the rotation of the cutters 38, 40 and 42 in the cutter head 46. As the cutter head 46 is swung forward toward the jack 30 to an extent determined by the engagement of the abutment 50 with the edge 52 of the pattern, the button 450 of the lever 54 rides down a lower lateral beveled face 452 (Figs. 2, 4, 10, 15 and 15A) of the cam 56, when said cam is positioned upon the holder 100 as viewed in Fig. 14 to accommodate a left sole, or rides down a lower beveled face 452a (Figs. 2, 4, 14 and 15A) of the cam when said cam is positioned upon the holder as viewed in Fig. 10 to accommodate a right sole, into engagement with a flat or plateau portion 454 (left work) or 454a (right work) of the cam to its dotted line position shown in Figs. 4, 14 and 15. Such movement of the lever 54 causes the shank reducing cutter 40 to be lowered to its effective position shown in Figs. 2 and 20, with the result that the cutter operates upon the rear portion of the shank of the sole together with the rounding cutter 38 as the cutter head 46 is moved forward.

The cam 56, which during forward movement of the cutter head 46 rotates the lever 54 clockwise as viewed in Figs. 2 and 4, and accordingly, through mechanism above described, depresses the rotary shank reducing cutter 40 to its effective position on the drive shaft 316, is provided with a slot 456 (Figs. 9, 10 and 15) and a pin receiving hole 458, the faces or plateau portions 454, 454a of the cam being flat and parallel to each other.

As above explained, the lateral margins of the cam 56 are beveled to provide the faces 452 or 452a down and up which the button 450 of the lever 54 rides as it approaches and leaves the bottom or active face 454, 454a of the cam 56 during forward and rearward swinging movements, respectively, of the cutter head 46.

The cam 56 may be quickly and effectively placed either face 454 or 454a downward upon

the pattern holder 100 of the jack 30, depending upon whether a left or right sole is to be operated upon, by sliding the cam to the left as viewed in Fig. 9 into a recess 460 of the holder 100 with portions of the cam at opposite sides of the slot 465 straddling a pin 462 (Figs. 9, 10 and 14) permanently screwed into the holder, a latch pin 464 slidably mounted in a bore 466 (Fig. 9) of the holder, at such time being depressed to a position below the hole 458 in the cam. Preparatory to reversing the cam 56 when it is desired to operate on right soles, after operating on left soles, for example, the pin 464 is depressed against the action of a spring 468, by sliding a manually operated plunger 470 movable in a bore 472 of the holder, to the right as viewed in Fig. 9 against the action of a spring 474 thereby causing a beveled face 476 of the rod to be forced against a correspondingly beveled face 477 of the pin. When the cam 56, which fits between the upper and lower faces of the recess 460 of the holder 100, is in its operative position in said holder, the plunger is released and, acted on by the spring 474, returns to its normal position shown in Fig. 9, the pin 464 being moved to its raised cam locking position by the spring 468.

When the cutter head 46 swings forward in response to rearward actuation of the lever 166 (Figs. 1, 11 and 13), the button 450 of the lever 54 travels down the lower beveled face 452 or 452a of the cam as above explained, and onto the bottom plateau or face 454 or 454a, such course being indicated by dot-dash lines 478 in Figs. 14 and 15. During such movement the shank reducing cutter 40 is depressed to its lowered effective position along the axis 44 of the drive shaft 316, the shank reducing cutter 40 together with the rounding cutter 38 operating upon the sole as illustrated in Fig. 20. The shank reducing cutter 40 when in its lowered effective position cuts deeper into the sole than does the roughing cutter 42, and accordingly, said roughing cutter has little if any effect in the removal of stock from the shank of the sole.

While the cam 56 moves with the jack 30 as above described past the cutter head 46, the abutment 50 is in engagement with the edge 52 of the pattern 34, the button 450 of the lever 54 engaging the cam, when left soles are being operated upon, along portions indicated by dotted lines 480, 480a (Figs. 14 and 15) and by dotted lines 482, 482a, for example. The lines 480 and 482 on the one hand, and the lines 480a and 482a on the other hand, represent the general paths of engagement of the button 450 with the cam 56 when the largest and smallest patterns 34 are on the jack 32, and accordingly, the largest and smallest soles are being operated upon.

Just before the abutment 50 engages the pattern 34, the brake 162 (Fig. 1) is released and the jack operating clutch 164 is engaged through mechanism described in detail in said Letters Patent 2,081,961 causing rotation of the gear 156 (Fig. 1), and accordingly, movement of the sliding support 78 together with the jack, to the left as viewed in Fig. 1, the cam 56 engaging the button 450 of the lever 54 along the left end of the line 480 or 480a (Fig. 15) which crosses a lower ridge 484 and rides up a trailing beveled face 486 of the cam 56. As the cam 56 moves away from the lever button 450, the lever 54, acted upon by the spring 442, swings counter-clockwise as viewed in Figs. 2 and 4 until the flange 444 on the rod 440 engages the stop shoulder 446. The gear 156 about this time is

engaged by the right circular portion of the rack 152 (Fig. 8) of the carriage 80 causing the jack 30, and accordingly, the sole clamped to the pattern 34 to be rotated in the then stationary support 78 past the rounding and roughing cutters 38 and 42 thereby rounding and roughing the margin of the heel end of the sole. Before the opposite end of the heel-breast line 26 of the sole 20 reaches the cutter head 46, an opposite straight portion of the rack 152 at such time having reached the gear 156, the lever button 450 travels down a beveled face 488 and over a lower ridge 490 of the cam 56 thus again engaging the lower face of the plateau 454 of said cam, with the result that the cutter 40 is again moved downward into its effective position along the axis 44 of the drive shaft 316 to start reducing and roughing the opposite, that is, the outer shank portion of the sole.

When the jack 30 has slid sufficiently for the outer end of the break line 24 of the sole 20 to pass the shank reducing cutter 40, the lever button 450 has traveled over a lower ridge 492 and up a lower beveled face 494 of the cam 56, said cam leaving the lever button 450, with the result that the shank reducing cutter again moves to its raised ineffective position in the cutter head 46. The jack 30 then continues to cause the forepart of the sole 20 on the pattern 34 to traverse the cutters 38, 40 to round and rough the forepart of the sole, after which the lever button 450 rides down a lower bevel face 496 and across a lower ridge 498 of the cam into engagement with the face or plateau 454 of the cam 56 before the inner end of the break line 24 of the sole 20 moves past the cutters, the cutter 40 at such time again being depressed to reduce the inner shank portion of the sole.

The carriage 80 has secured to it a block 500 (Figs. 8 and 11) which upon completion of a cycle of the carriage engages a dog 502 pivotally mounted in the machine frame 70, thereby disengaging the clutch 164 and applying the brake 162, with the result that the carriage comes to rest in the position shown in Figs. 1, 8 and 11. The mechanism for effecting this operation is identical with that disclosed in Letters Patent 2,081,961 and need not be further described herein. The carriage 80 comes to rest when the lever button 450 arrives back at its starting position, the cutter head 46 thereafter being moved to its rear or retracted position away from the jack 30 against the action of the spring 48 by the link 256 actuated by mechanism above referred to.

It will be clear from the foregoing that the paths of engagement of the cam 56 with the lever button 450 differ in accordance with the size and shape of the pattern 34, and accordingly, the sole which is trimmed to an outline determined by the pattern, the paths in the case of a large pattern being indicated by the chain lines 480, 482 and in the case of a small pattern being indicated by the chain lines 480a and 482a as above explained. It will be apparent that when the button 450 of the lever 54 is in engagement with the plateau portion 454 of the cam 56 the shank reducing cutter 40 is in its lowered effective position in the sole and since the ridges 492, 498, which may be referred to as edges, are inclined generally lengthwise of the paths or loci of engagement 480, 480a, 482, 482a of the button with the cam it will be clear that the shank reducing cutter is moved toward or away from its effective position to control the positions

of the forward ends of the shank reducing cuts in accordance with the sizes of the patterns 34 and therefore the soles to be produced. A cam so constructed and arranged may be defined as a graded cam.

Since the bores or holes 190 in the patterns 34 of different sizes are spaced a constant distance from central lengthwise points of the patterns respectively, it will be apparent that outer ends of the break lines 24 of patterns of different sizes are spaced different lengthwise distances D, D', D'' from the central portions of said patterns as indicated in Fig. 14. In order to insure that soles 20 of different sizes shall be effectively shank reduced, special attention being given to having the reduced shanks of the soles extend forward to opposite ends of the break lines of the soles, the beveled faces 494, 496 which may be referred to as ramps, and accordingly, the ridges or edges 492, 498, which are formed between the plateau portions 454 and the ramps of the cam, are inclined rearwardly and inwardly of the patterns as above described, said ridges or edges and the elements of the beveled faces 494, 496 being substantially parallel to lines 504, 506 (Fig. 14) which includes substantially the outer ends of break lines of a run of sizes of patterns. The edges 492, 498 may be described as being formed near one end of the cam 56 and as being inclined to the path of movement of the cam as well as being inclined to each other and extending toward an opposite end of the cam. By providing a graded reversible cam 56, such as above described, it will be clear that the cam in operating upon left and right soles will engage the button 450 of the lever 54 at the proper time to insure that the shank reducing cuts of soles of different sizes shall extend to but not beyond the break lines of the soles.

In various types of shoes, for example, women's shoes which have wood heels, the heel seat portion of the sole is reduced after attachment of the shoe to the shoe upper to form a heel seat tab (not shown) and heel seat heel-breast receiving shoulders (not shown) against which the breast of the heel abuts. Accordingly, in this type of shoe the shank reducing cuts may extend rearward of the heel-breast line 26 without being objectionable since the margins of the heel seat portion of the sole are removed during a subsequent heel seat fitting operation. It is, however, important that the shank reducing cuts extend only to the opposite ends of the break line 24 of the sole, as above described, in all types of shoe construction. It has been found that many shoemakers desire to vary the forward extent of the shank reducing cut at one side of the shoe without changing the forward extent of the shank reducing cut at the other side of the shoe. With this in mind the cam 56 when used in the manufacture of women's shoes having wood heels, for example, may be advantageously made in three parts, lateral portions 512, 514 (Figs. 16 and 17) of a cam 518 being slidably adjustable lengthwise with relation to a central T-shaped portion 516 of the cam which will be referred to as the modified cam. The central T-shaped portion 516 of the cam has threaded into it screws 519 which pass through elongated slots 520 (Fig. 16) in the side portions 512, 514, and may be loosened preparatory to adjusting said side portions with relation to the central T-shaped portion. To facilitate the proper adjustment of the side portions 512, 514 relatively to the central T-shaped portion 516, said side and central portions are suit-

ably calibrated as shown at 521. The central T-shaped portion 516 is provided with a slot 522 and a hole 523 corresponding to the slot 456 (Figs. 9, 10 and 15) and the hole 458 of the cam 56.

In order that the shaft 268 (Figs. 1, 4 and 12) through which the cutters 38, 40 and 42 are rotated, may be stopped to change cutters, for example, without shutting off the motor drive 524 (Fig. 1) of the machine, there is provided between the shaft 268 and a skewed gear 526 secured to the upper end of a shaft 528 (Figs. 1 and 8) corresponding to the shaft 42 in Letters Patent 2,081,961 a clutch 530 (Figs. 1 and 12) which may be engaged or disengaged by moving a hand lever 531. In driving relation with the skewed gear 526 is a skewed gear 532 (Fig. 12) mounted for rotation on a sleeve 534 which is keyed to a reduced end of the shaft 268 and bears against a collar 536 loose on the shaft and engaging a shoulder 538 of the shaft and an inner race of a ball bearing 540 for said shaft. The skewed gear 532 has formed integral with it a hub 542 engaging the collar 536 and a tapered driving drum 544 arranged in opposed relation to an outer driven drum 546 rotatable upon a spacer 548 which is mounted upon the shaft. The left end of the spacer 548 bears against the sleeve 534 and the right end of the spacer engages a disk 550 secured by a screw 552 to the drive shaft 268. Secured to the sleeve 534 and slidably fitting in three circumferentially spaced recesses 554 of the drum 546 are pins 556 which drive the sleeve in response to rotation of the drum 546. Housed in recesses 558 of the driven drum 546 and engaging the disk 550 are springs 560 which constantly urge the driven drum 546 into forced engagement with the driving drum 544.

The driven drum 546 has secured to it by one or more screws 562, a plate 564 which may be regarded as part of the drum, said plate forming with the major portion of the drum a circumferential groove 566 in which fit a pair of fingers 568 secured by screws 570 to a yoke 572 formed integral with a shaft 574 which slidably fits in a cylindrical bore 576 of the machine frame 70 and has secured to it by one or more screws 578, a cam 580. The yoke 572 is held against rotation by engagement of its lateral portions in longitudinal slots 582 formed in the inner face of the machine frame 70. The guiding of the yoke 572 in the direction of the axis of rotation of the shaft 268 is assisted by a pin 584 secured to the frame and slidably fitting in a bore 586 of the yoke. Loosely mounted upon the shaft 574 of the yoke 572 and interposed between the frame 70 and the cam 580 is an actuating wedge 588 (Figs. 1 and 12) to which the manually operated handle 531 is secured. When the handle 531 is in the position shown in Figs. 1 and 12 the yoke 572 is permitted to assume an active position enabling the springs 560 to force the outer drum 546 against the inner drum 544 with the result that the skewed gear 532 drives, through the inner drum 544, the outer drum 546, the pins 556 and the sleeve 534, the shaft 268. When it is desired to stop the shaft 268 preparatory to changing the cutters 38, 40 and 42, the handle 531 is moved toward the observer as viewed in Figs. 1 and 12, causing the wedge 588 to slide the cam 580 and accordingly the yoke 572, to the right thereby moving the driven drum 546 out of driving relation with the driving drum 544. The actuating wedge 588 is held in its clutch engaging and disengaging positions by a spring-pressed

plunger 592 which is slidably housed in the machine frame 70 and is adapted to register in either one of two recesses 594 (only one shown) of the wedge.

In order to insure against the abutment 59 (Figs. 1 to 5 inclusive) carried by the cutter head 46 striking the pattern 34 with too much force during forward swinging movement of the arm 62, the cutter head 46 carries a dash pot 596 (Figs. 2 and 11) comprising a piston 600 which is constantly urged to the left as viewed in Fig. 11 by a spring 602. The piston 600 of the dash pot 596 carries a roller 604 constructed and arranged, upon forward movement of the arm 62 to engage a face 606 of a check cam 608 which is pivotally connected to a lever 612 and biased for clockwise movement as viewed in Fig. 11 by a spring 610, said cam being guided for movement by the lever 612 and the fixed pin 248 which passes through a slot 618 of the check cam. The forward end of the lever 612 is secured to a feeler 614 having a face 616 constructed and arranged to engage the edge of the pattern 34 on the jack 30. When there is no pattern 34 in the machine the various parts just described are in their positions illustrated in Fig. 11, counterclockwise movement of the feeler 614 being limited by the engagement of the right end of the slot 618 with the pin 248, the feeler at such time being spaced slightly from the left pin 188 of the holder 100.

Should the clutch 164 (Figs. 1 and 11) be tripped by swinging the hand lever 166 (Figs. 1, 11 and 13) forward, when there is no pattern 34 on the jack 30, it will be clear that if no safety mechanism were provided, the cutter head 46 would swing forward under the action of the spring 48 and strike the jack. To insure against collision between such parts and also to prevent the tripping of the clutch 164 when there is no pattern in the machine, said machine is provided with the following safety mechanism. Such mechanism comprises a stop finger 620 which is pivotally mounted upon the pin 248 and is constantly urged clockwise as viewed in Fig. 11 by a leaf spring 622, one end of which bears against the finger and the other end of which is secured to the machine frame 70. When there is no pattern 34 upon the holder 100, the right end of the slot 618 in the check cam 608 is in engagement with the stop pin 248 as illustrated in Fig. 11, a lug 624 secured to the bottom of the check cam being in a position to be engaged by a hook-shaped projection 626 of the stop finger 620.

The hand lever 166 is pivoted upon a pin 628 secured to the machine frame 70 and has pivotally connected to it, above said pin, a rod 630. A lower bifurcated end of the lever 166 carries a pin 634 extending through a slot 632 formed in a link 633 which is pivoted at its rear end to a slide 635 reciprocable in the machine frame 70. The slide 635 is operatively connected, through mechanism disclosed in Letters Patent 2,081,961, to a pawl or detent (not shown) which corresponds to the pawl locking dog or detent 464 disclosed in said Letters Patent and upon release of which the cutter head carrying arm 62 is permitted to swing forward under the action of the spring 48. The safety rod 630 carries a pin 634 (Fig. 11) extending through a slot 636 at the right end of a bell crank lever 638 fulcrumed on a pin 640 secured to the main frame, the lever being constantly urged counterclockwise by a spring-pressed plunger 642 movable in a

bore of a boss of said lever. Pivotally connected to the left arm of the bell crank lever 638 is a link 644 having at its forward end a slot 646 through which passes a pin 648 carried by the finger 620 which, as above stated, has the hook-shaped portion 626. When there is no pattern 34 on the holder 100, and accordingly, the lug 624 on the check cam 608 is in its position shown in Fig. 11 in front of the extension 626 of the finger 620, the rod 630, and accordingly, the lever 166 cannot be moved a substantial distance forward, it being possible to move the lever forward until the pin 648 engages the forward end of the slot 646 in the bell crank lever 638. Accordingly, the slide 635 is prevented from being moved rearward sufficiently to operate the above-mentioned pawl corresponding to the pawl 464 disclosed in Letters Patent 2,081,961.

When the check cam 608 is moved to the right, as viewed in Fig. 11 by reason of a pattern 34 having been positioned upon the holder 100, the lug 624 slides from its position in front of the projection 626 of the finger 620 so that the hand lever 166 may be moved sufficiently forward to actuate the pawl, which corresponds to the pawl 464 of said Letters Patent 2,081,961, thereby starting the machine.

When the cutter head carrying arm 62 is moved forward by the action of the spring 48, the face 606 of the check cam 608 is engaged by the roll 604 of the piston 600 to insure that the abutment 50 carried by and, in effect, forming part of the depending bracket 51 of the cutter head 46, shall be eased into engagement with the edge face 52 of the pattern 34. The check cam 608 is moved into different operating positions in accordance with the size of the pattern 34, the construction and arrangement being such that the checking effect of the cam 608 on the cutter head 46 shall be approximately the same irrespective of the size of the pattern.

In order to insure against the cutter head carrying arm 62 swinging forward sufficiently to cause the cutter head 46 to collide with the jack 30, should the pawl 464 of the machine disclosed in Letters Patent 2,081,961 be accidentally moved away from a shoulder of a cam with which it engages, by a mechanic adjusting the machine, the finger 620 is provided with a shoulder 652 shaped and arranged to be engaged by a lug 654 secured by screws 656 to the arm 62, this portion of the safety mechanism being similar to corresponding mechanism disclosed in said Letters Patent 2,219,341. When there is a pattern 34 in the machine and the lever 166 is moved forward to start the machine through its operative cycle, the stop finger 620 is swung counterclockwise, as viewed in Fig. 11, into such a position as to be clear of the path of movement of the lug 654 on the cutter head 46.

In the machine disclosed in Letters Patent 2,081,961 the cutter head 46 is moved to its retracted or idle position after movement of the jack 30 has ceased, by a strap (not shown) mounted upon a shaft. As above explained, in the present illustrative machine, as in the machine disclosed in Letters Patent 2,219,341, the cutter head 46 is moved to its retracted position by the link 256 (Figs. 2, 4 and 11), the forward end of which is pivotally connected to the cutter head 46 and the rear end of which is pivotally connected to the arm 254 secured to the upper end of the shaft 252. In view of the fact that mechanism for moving the cutter head 46 rearward from its operative position and for limiting

the speed of the cutter head toward its forward operating position is disclosed in the above-mentioned Letters Patent 2,219,341, no further description of this particular subject-matter is believed to be necessary herein.

When the machine is in use, the motor drive 524 runs continuously and through mechanism disclosed in Letters Patent 2,081,961 drives the shaft 528, the rounding and the shank reducing and roughing cutters 38, 40 and 42 rotating when the clutch 530 is engaged. When the machine is idle the swinging arm 62 which carries the cutter head 46, is held in its rearward position against the action of the spring 48 (Figs. 1 and 11) by the above-mentioned pawl 464 disclosed in Letters Patent 2,081,961, the clutch 164 being disengaged and the brake 162 holding the jack against movement.

The treadle 126 is then depressed against the action of the springs 125, 140 to raise the clamp 32 preparatory to placing a block sole on the pattern 34 mounted upon the jack 30. The treadle 126 is thereafter released permitting said block sole to be clamped by spring action against the pattern 34. The operator next swings the hand lever 166 forward to release the pawl 464 disclosed in said Letters Patent 2,081,961, with the result that the arm 62 swings forward toward the jack 30 by the action of the spring 48 until the abutment 50 engages the pattern 34, the dash pot 596 carried by said arm insuring against the cutters carried by the cutter head 46 suddenly biting into the sole and also insuring against the abutment striking against the pattern with excessive force. The rest position of the jack 30 is such that the cutters 38, 40 and 42 initially move forward against the rear shank portion of the sole.

After the abutment 50 of the cutter head 46 has moved into engagement with the edge of the pattern 34, the clutch 164 controlled by mechanism described in detail in said Letters Patent 2,081,961 is engaged, with the result that the shaft 154 is rotated and the jack is caused to slide and rotate as above described with the result that the entire periphery of the sole clamped against the pattern is traversed past the cutters 38, 40 and 42, the block 500 on the carriage 80 engaging the dog 502 as the jack approaches its rest position to cause the clutch 164 to be disengaged and the brake 162 to be applied when the jack has completed its cycle. When the jack has come to rest, the arm 62 is automatically swung rearward to swing the cutter head 46 and accordingly the cutters 38, 40 and 42 to their retracted starting positions. The operator then depresses the treadle 126 to permit the operator to remove the sole which has been operated upon, from the machine and place another sole to be operated upon, in the machine.

Having thus described my invention, what I claim as new and desire to secure by Letters Patent of the United States is:

1. In a machine for operating upon soles, a holder for positioning and supporting a pattern, a clamp for forcing a block sole against the pattern, means for moving the clamp with relation to the holder to facilitate the placing of said sole on the holder, a carrier, rounding shank reducing and roughing cutters mounted in the carrier for rotation about a common axis, means for sliding and rotating the holder and the clamp to move the pattern and accordingly the sole in a predetermined path, an abutment mounted upon the carrier, means for moving the carrier toward the holder and for yieldingly forcing the abutment

of the carrier against an edge of the pattern while said pattern is moved in said path to cause the cutters to round, shank reduce and roughen the sole, a cam movable with the holder, and mechanism actuated by the cam during its movement with the holder for moving at predetermined times the shank reducing cutter along its axis of rotation into an effective position to cause said cutter to operate upon the sole at selected localities.

2. In a machine for operating upon soles, a holder for a block sole, a cutter head, a cutter rotatably mounted in the cutter head, means for effecting relative movement of the holder and the cutter head to cause relative traversing of the cutter and the margin of the sole, a movable graded cam, and mechanism comprising an element which is moved in and out of engagement with the cam and the path of engagement of which with the cam during relative movement of the holder and the cutter head varies in accordance with the desired size of the sole being operated upon, said mechanism being responsive to movement of the cam for moving the cutter relatively to the cutter head to and from an operative position at predetermined times in accordance with the desired size of the sole and accordingly said path of engagement to cause the sole to be reduced at selected localities during relative movement of the holder and the cutter head.

3. In a machine for operating upon soles, a holder for positioning and supporting a pattern, a clamp for forcing a sole against the pattern, a cutter head, three or more cutters rotatable about a common axis in the cutter head, an abutment mounted upon the cutter head, means for rotating the cutters, means for yieldingly urging the cutter head in one direction to force the abutment against an edge of the pattern to position the cutters in predetermined relation to said edge, means for sliding and rotating the holder to cause the margin of the sole to traverse the cutters to operate upon the sole, and means comprising a cam movable with the holder for moving one of said cutters lengthwise of said axis with relation to the other cutters.

4. In a machine for operating upon soles, a jack mounted for alternate sliding and rotary movement in a predetermined path, means movable with the jack for securing a pattern and a sole together for movement with the jack, a cutter head, a cutter rotatable in the cutter head for movement about an axis, said cutter head being movable toward and away from the pattern and being held yieldingly against said pattern as the pattern and the sole are moved with the jack, a graded cam movable in timed relation with the jack, and mechanism movable with the cutter head, said mechanism comprising an element which is engaged by different portions of the cam, the loci of engagement of the element and the cam during movement of the jack varying in accordance with the size of the pattern in order to move the cutter in the cutter head lengthwise of its axis of rotation to and from an operative position in engagement with the sole as predetermined portions of the patterns traverse the cutter head.

5. In a machine for operating upon soles, a jack, means for positioning a pattern upon the jack, means for clamping a sole against the pattern and the pattern against the jack, a cutter head, a plurality of cutters rotatable about a common axis in the cutter head, said cutter head

being movable from an idle position spaced a considerable distance from the jack to operative positions determined by the engagement of the cutter head with the pattern, means for rotating the cutters in the cutter head, means for urging the cutter head and the cutters toward the sole, means for effecting translatory and rotary movement of the jack to traverse the periphery of the sole past the cutters, a cam carried by the jack, and mechanism actuated by the cam for moving one of the cutters at predetermined times lengthwise of said axis with relation to one or more of the other cutters.

6. In a machine for operating upon soles, a cutter head, means for supporting in clamped relation a pattern and a block sole, a rounding cutter and a shank reducing cutter rotatable in said cutter head about a common axis, means for effecting relative movement of said first-named means and said cutter head in a predetermined path to cause the rounding cutter to act upon the block sole to round said sole to the outline of the pattern, and mechanism comprising a cam for moving the shank reducing cutter lengthwise of said axis with relation to the rounding cutter during predetermined portions of said relative movement of the first-named means and the cutter head in said path to shank reduce the sole while the sole is being rounded.

7. In a machine for operating upon soles, means for supporting in clamped relation a pattern and a block sole, a cutter head, a rounding cutter and a shank reducing cutter rotatable in said cutter head about a common axis, means for effecting relative movement of said first-named means and said cutter head in a predetermined path to cause the rounding cutter to round said sole to the outline of the pattern, a cam fixed to said first-named means, and mechanism which is carried by the cutter head and comprises a follower constructed and arranged for engagement with said cam during portions of said relative movement of the cutter head and the first-named means, to move the shank reducing cutter with relation to the rounding cutter from an ineffective to an effective trimming position in order to reduce the shank portion of the sole at selected localities.

8. In a machine for operating upon soles, a cutter head, means for supporting in clamped relation a pattern and a block sole, rounding and shank reducing cutters mounted for movement about a common axis in said head, means for effecting relative movement of said first-named means and said cutter head to cause the rounding cutter to round the sole to the outline of the pattern, and mechanism comprising a graded cam and a follower for moving the shank reducing cutter lengthwise of said axis with relation to the rounding cutter during predetermined portions of said relative movement of the cutter head and said means to shank reduce the outsole, portions of different shape of said cam being engaged by the follower in accordance with the outline of the pattern.

9. In a machine for operating upon soles, a cutter head, a rounding cutter, a forepart reducing and roughing cutter, a shank reducing cutter, said cutters being mounted for rotation about a common axis in the cutter head, means for sliding and rotating a pattern and a sole clamped to said pattern, means for yieldingly urging the cutter head against the pattern to cause, during sliding and rotation of the pattern and the sole, the cutters to operate upon the sole, means for mov-

ing the rounding and the forepart reducing and roughing cutters lengthwise of said axis into different adjusted positions in said cutter head, means for moving the forepart reducing and roughing cutter lengthwise of said axis in the cutter head into different adjusted positions with relation to the rounding cutter, means for moving the shank reducing cutter in said cutter head a fixed distance lengthwise of said axis to move such cutter from an ineffective position to an effective position, during predetermined portions of the movement of the pattern to shank reduce the sole, and means for moving the shank reducing cutter lengthwise of said axis in the cutter head to vary the ineffective position of the cutter, and accordingly, the effective position of said cutter along said axis.

10. In a machine for operating upon soles, a cutter head having an abutment, sole rounding and shank reducing cutters movable in said head about a common axis, a jack for supporting a pattern, clamps for forcing a sole against said pattern, means for yieldingly moving the cutter head toward said pattern to positions determined by the engagement of the abutment with said pattern, means for sliding and rotating the jack, and accordingly, the pattern to cause the margin of the sole to traverse said cutters, a graded cam carried by and movable with said jack, and mechanism comprising a cam follower carried by the cutter head and constructed and arranged to be engaged by different portions of the cam, in accordance with the shape of the pattern to the outline of which the sole is being rounded, in order to shank reduce the sole at the proper positions.

11. In a machine for operating upon soles, a cutter head having an abutment, sole rounding and shank reducing cutters rotatable in said cutter head about a common axis, a jack for supporting a pattern, clamps for forcing a sole against said pattern, means for yieldingly moving the cutter head towards said pattern to positions determined by the engagement of the abutment with said pattern, means for sliding and rotating said jack and accordingly said pattern to cause the margin of the sole to traverse said cutters, a cam carried by and movable with said jack, and mechanism responsive to movement of the cam for moving the shank reducing cutter lengthwise of its axis of rotation with relation to the rounding cutter to an effective position during said traversing of the sole to cause the sole to be shank reduced at selected localities.

12. In a machine for operating upon soles, a cutter head having a rotatable spindle, a rounding cutter and a margin reducing and roughing cutter keyed for rotation with the spindle, abutments carried by the spindle, a spring arranged between the cutters and constructed and arranged to force said cutters against said abutments respectively, means for initially adjusting one of the abutments to vary the axial position of the margin reducing and roughing cutter with relation to the rounding cutter, a sleeve rotatable with the spindle, a shank reducing cutter carried by the sleeve, and means for moving the sleeve axially in the cutter head.

13. In a machine for operating upon soles, means for supporting a pattern and for clamping a sole against said pattern, a cutter head, a rounding cutter and a sole reducing and roughing cutter rotatable in said cutter head about a common axis, means for effecting relative movement between the cutter head, on the one hand,

and the pattern and the sole, on the other hand, in a predetermined path to effect simultaneous rounding of the sole and reducing and roughing of portions of the margin of said sole, said cutter head comprising a driven spindle to which the cutters are keyed, a pair of spaced abutments, and a spring which is interposed between the cutters and urges said cutters away from each other on the spindle into engagement with the abutments respectively, the abutment against which the reducing and roughing cutter is forced being mounted for adjustment in the cutter head axially of the cutters.

14. In a machine for operating upon soles, means for supporting a pattern and for clamping a sole against said pattern, a cutter head, a rounding cutter, a shank reducing cutter, a forepart reducing and roughing cutter, said cutters being rotatable in said cutter head about a common axis, means for effecting relative movement between the cutter head, on the one hand, and the pattern and the clamped sole, on the other hand, in a predetermined path to cause rounding of the sole, shank reducing of the sole and the reducing and roughing of the forepart of the sole, said cutter head comprising a driven spindle to which the rounding cutter and the margin reducing and roughing cutter are keyed, a pair of abutments carried by the cutter head, a spring which urges the rounding and the margin reducing and roughing cutters away from each other on the spindle into engagement with the abutments respectively, the abutment against which the margin reducing and roughing cutter is forced being mounted for adjustment in the cutter head axially of the cutters, a sleeve, to which the shank reducing cutter is secured, rotatable with the spindle, and means for moving the sleeve and accordingly the shank reducing cutter lengthwise of said axis during predetermined portions of the relative movement of the cutter head and said means to move the shank reducing cutter into effective position in the cutter head to shank reduce the sole.

15. In a machine for operating upon soles, rounding and shank reducing cutters, rotatable about a common axis, means for rotating said cutters, a jack for supporting a pattern, a clamp for forcing a sole against said pattern, means for sliding and rotating the jack and said clamp to cause the periphery of the sole to traverse said cutters, a cam carried by the jack, and mechanism movable in response to movement of the cam for moving the shank reducing cutter lengthwise of its axis of rotation relatively to the rounding cutter during predetermined portions of the sliding movement of the jack to cause the shank reducing cutter to shank reduce the sole.

16. In a machine for operating upon soles, a jack for supporting a pattern, a clamp for securing the pattern to the jack and a sole to the pattern, means for sliding and rotating the jack to move the pattern and the sole in a predetermined path, a cutter head having an abutment, a shank reducing cutter rotatable in the cutter head, mechanism comprising a follower for moving the shank reducing cutter lengthwise of its axis of rotation to and from an effective cutting position, means for yieldingly forcing said abutment against an edge of the pattern as said pattern is moved in said predetermined path to position the cutter head in a desired position with relation to the pattern, a cam which is secured to and is movable with the jack and which has opposite sides graded

to accommodate runs of sizes of left and right soles respectively, said follower being constructed and arranged to be engaged by an active side of the cam during movement of the jack, the loci of engagement between the cam and the follower varying in accordance with the size of the pattern to cause through said mechanism, the moving of the shank reducing cutter lengthwise of its axis of rotation to and from said effective cutting position to shank reduce soles of different sizes to but not forward of the break lines of soles.

17. In a machine for operating upon soles, a holder for a pattern, a clamp for securing a sole to the pattern, a cutter head yieldingly moved toward the holder, means for effecting sliding and rotary movement of the holder in a predetermined path, a shank reducing cutter rotatable about an axis in the cutter head, mechanism which comprises a follower and is carried by the cutter head and in response to movement of which the cutter is moved lengthwise of its axis of rotation between effective and ineffective positions in the cutter head, a graded cam which is secured to the holder for movement therewith, said cam having a flat face which is arranged parallel to its path of movement and has one end comprising ramps which form with said face edges inclined toward each other and toward the opposite end of the cam and different portions of which are engaged by the follower in accordance with the size of the patterns to cause said cutter to move to and from its effective position during different portions of the movement of the holder in said predetermined path to shank reduce soles of different sizes by cuts which terminate at the break lines of said soles.

18. In a machine for operating upon soles, a jack for supporting a pattern, spring actuated means, a cutter head movable by the spring actuated means from an idle position remote from said pattern to an operative position in engagement with the pattern, mechanism comprising a clutch, said mechanism being constructed and arranged upon engagement of said clutch to cause movement of the jack in a predetermined path, means comprising a detent constructed and arranged when in an effective position to hold the cutter head in its idle position and the clutch disengaged and when moved to an ineffective position to cause the cutter head acted on by the spring actuated means to be swung to its operative position and to cause the clutch to be engaged, mechanism comprising an abutment which is in a stop position when there is no pattern on the jack, a safety finger, and a hand lever which is operatively connected to said detent and to the safety finger and is held against sufficient movement to move the detent from its operative position, by the engagement of the finger with said abutment in stop position, said abutment being movable to an ineffective position when there is a pattern in the machine thereby enabling the safety finger to move freely when the hand lever is actuated, and accordingly, to cause movement of the detent, therefore enabling the cutter head to move from its idle to its operative position and also to cause engagement of the clutch for moving the jack in said predetermined path.

19. In a machine for operating upon soles, a shank reducing cutter, a carrier for said cutter, said carrier having an abutment, a jack, means for positioning a pattern on said jack and for clamping a sole against the pattern, means

for yieldingly urging the carrier toward the jack to an extent determined by the engagement of the abutment with the edge of the pattern, means for sliding and rotating the jack to cause a sole on the pattern to move in a predetermined path past the carrier, mechanism which is operatively connected to the carrier and comprises a follower, said follower upon movement of the jack past the carrier engaging the cam along different paths in accordance with the size of the pattern to cause said cutter acted upon by said mechanism to move to and from an effective position in the carrier to shank reduce soles of different sizes at predetermined localities.

20. In a machine for operating upon soles, a cutter head, a shank reducing cutter which is rotatable in said cutter head and is movable in said head lengthwise of its axis of rotation to and from an effective position, a holder for a pattern, a clamp for forcing a sole against said pattern, resilient means for forcing the cutter head against an edge of said pattern, means for moving the holder, and accordingly, the pattern and the sole clamped thereto in a predetermined path while the cutter head engages said edge of the pattern, a graded cam which is secured to the holder, and mechanism which is carried by the cutter head and has a follower which upon movement of the holder in said path engages the cam along loci extending along different portions of the cam in accordance with the size of the pattern to effect movement of the cutter to and from its effective position in said head to cause soles on said pattern to be shank reduced at predetermined localities.

21. In a machine for operating upon soles, a holder for interchangeably receiving patterns of different sizes, a clamp for securing a sole to the selected pattern, a cutter head, means for yieldingly moving the cutter head toward the holder, means for effecting sliding and rotary movement of the holder in a predetermined path, a shank reducing cutter movable about an axis in the cutter head, mechanism which comprises a follower and is carried by the cutter head and in response to movement of which the cutter is moved lengthwise of its axis of rotation into different positions in the cutter head, and a graded cam which is secured to the holder for movement therewith, said follower upon movement of the holder in said path being engaged by said cam along loci extending along different portions of the cam in accordance with the size of the pattern to cause soles on said pattern to be shank reduced at selected localities, said cam having lateral halves for varying lengthwise of the sole the position of the shank reduction at one side of the sole with relation to the shank reduction at the other side of the sole.

22. In a machine for operating upon soles, a holder for interchangeably receiving patterns of different sizes, a clamp for securing a sole to the selected pattern, a cutter head, means for yieldingly moving the cutter head toward the holder, means for effecting sliding and rotary movement of the holder in a predetermined path, a shank reducing cutter movable about an axis in the cutter head, mechanism which comprises a follower and is carried by the cutter head and in response to movement of which the cutter is moved lengthwise of its axis of rotation into different positions in the cutter head, and a graded cam which is secured to the holder for movement

therewith, said cam having lateral halves provided with follower engaging portions having edges arranged approximately parallel to lines respectively including the outer ends of break lines of patterns of different sizes positioned upon the jack, each of the lateral halves of the cam being adjustable lengthwise of the pattern with relation to the other half.

23. In a machine for operating upon soles, 10 a holder for positioning and supporting a pattern, a clamp for forcing a blank sole against the pattern, means for moving the clamp with relation to the holder to facilitate the placing of the sole on the holder, a carrier, rounding and shank reducing cutters mounted in the carrier for rotation about a common axis, means for sliding and rotating the holder and the clamp to move the pattern and accordingly the sole in a predetermined path, an abutment mounted upon the 20 carrier, means for moving the carrier toward the holder and for yieldingly forcing the abutment of the carrier against an edge of the pattern while said pattern is moved in said path to cause the cutter to round and shank reduce the sole, a cam 25 movable with the holder, and mechanism activated by the cam during movement of the cam with the holder for moving at predetermined times the shank reducing cutter with relation to the rounding cutter along its axis of rotation into 30 an effective position to cause the shank reducing cutter to operate upon the sole at selected localities.

24. In a machine for operating upon soles, a 35 holder for a block sole, a cutter head, a cutter rotatably mounted in the cutter head, means for effecting relative movement of the holder and the cutter head to cause relative traversing of the cutter and the margin of the sole, a movable cam, and mechanism which comprises a cam engaging 40 element and which is responsive to movement of the cam and is operatively connected to the cutter, said cam having a ramp, a face and an edge defined by the intersection of said ramp and said face, said ramp during relative movement of the 45 holder and the cutter head being constructed and arranged to be engaged by said element to effect transfer of the cutter from an idle position away from the sole to an operative position in the sole or from an operative position in the sole to an 50 idle position away from the sole, said face being constructed and arranged to be engaged by said element to maintain said cutter in its operative position during relative movement of the holder and the cutter head, a section of said edge being 55 inclined to the path of relative movement of the holder and the cutter head and different portions thereof being engaged by said element at different lengthwise positions in said path in accordance with the size of the sole being operated 60 upon.
